UNITED STATES PATENT OFFICE.

MORRIS KLEIN, OF OAKLAND, CALIFORNIA.

HORSESHOE.

976,579.

Specification of Letters Patent. Patented Nov. 22, 1910.

Application filed April 27, 1910. Serial No. 557,986.

To all whom it may concern:

Be it known that I, MORRIS KLEIN, a citizen of the United States, residing at Oakland, in the county of Alameda and State 5 of California, have invented certain new and useful Improvements in Horseshoes, of which the following is a specification, reference being had therein to the accompanying drawing.

10 This invention relates to horseshoes, and the principal object of the same is to provide novel means whereby the shoe may be rigidly but detachably fastened to a hoof without the necessity of employing nails or 15 other hoof-penetrating fastening means.

In carrying out the objects of the invention generally stated above it will be understood, of course, that the essential features thereof are necessarily susceptible of changes 20 in details and structural arrangements, one preferred and practical embodiment of which is shown in the accompanying drawings, wherein:—

Figure 1 is a view in side elevation showing the improved shoe clamped to a hoof. Fig. 2 is a top plan view of the shoe. Fig. 3 is a view in side elevation of the shoe showing the clamping means released. Fig. 4 is a fragmentary sectional view taken on 30 the line A—A, Fig. 1.

Referring to said accompanying drawings by numerals, 1 designates the body of the improved shoe which is of the usual or any preferred shape and provided with the toe 35 and heel calks 2—3. The upper surface of the body 1 is partly surrounded by an upstanding flange 4 which is inwardly inclined, the inclination of said flange being greatest at the front of the shoe and merging into a 40 substantially straight wall 5 on one side of the body. Said flange extends from one heel around said body to a point intermediate of the other heel and the toe calk. Beyond the cut-away portion of said flange, the body 45 is provided with outstanding laterally projecting dovetailed lugs 6 which provide between them the correspondingly shaped recesses 7.

A latch 8 which is shaped similar to and 50 forms a continuation of flange 4, is hinged to said flange, said latch having its under-surface provided with dovetailed lugs 9 for interlocking engagement with recesses 7 and recesses 10 for interlocking engagement with 55 lugs 6. Lugs 9 of the latch are provided with openings 11 which aline with similar

openings 12 formed in the inner wall of recesses 7 when said lugs are in interlocked engagement to permit said latch to be detachably fastened to body 1 by the screws or 60 bolts 13.

In use, the latch is raised relative to body 1 and a hoof fitted on body 1 within the flange 4. The latch is then rocked to interlocking engagement with body 1, and by 65 means of the fasteners 13 the shoe is locked to the hoof.

It will be seen that the improved shoe may be readily attached to a hoof and rigidly locked thereon without the use of the usual 70 hoof-penetrating fasteners, and also that the same may be readily removed.

What I claim as my invention is:—

1. A horseshoe comprising a body, a hoof-engaging flange partly surrounding said 75 body, latching lugs carried by said body at one end of said flange, a latch hinged to said flange and forming a continuation of said flange, said latch adapted for interlocking engagement with said lugs, and means for 80 rigidly but detachably locking said flange to said body.

2. A horseshoe comprising a body provided with lugs and recesses adjacent one heel portion, a hoof-engaging flange carried 85 by said body and extending from one heel thereof and terminating adjacent said lugged and recessed portion, and a latch hinged to said flange and forming a continuation thereof, said latch provided with 90 lugs and recesses adapted for interlocking engagement with the lugs and recesses of said body.

3. A horseshoe comprising a body provided with laterally projecting dovetailed 95 lugs adjacent one heel portion thereof, an inwardly inclined upstanding hoof-engaging flange carried by said body and extending from said lugs around the body to the opposite heel thereof, a latch pivoted to said 100 flange and forming a continuation thereof, said latch provided with lugs and recesses adapted for interlocking engagement with the lugs of the body, and detachable fastening means for locking said latch to said 105 body.

In testimony whereof I hereunto affix my signature in presence of two witnesses.

MORRIS KLEIN.
